UNITED STATES PATENT OFFICE.

JOHN NEDERLAND, OF NEW YORK, N. Y., ASSIGNOR OF ONE-HALF TO MAX KAMERAS,
OF NEW YORK, N. Y.

CIGARETTE-CASE.

1,176,088.

Specification of Letters Patent. Patented Mar. 21, 1916.

Application filed November 27, 1914. Serial No. 874,251.

To all whom it may concern:

Be it known that I, JOHN NEDERLAND, a subject of the Czar of Russia, residing at New York, in the county of New York and 5 State of New York, have invented new and useful Improvements in Cigarette-Cases, of which the following is a specification.

This invention relates to cigarette holders and it consists in the novel features herein-10 after described and claimed.

An object of the invention is to provide in combination with a case adapted to contain cigarettes a holder of simple and durable structure adapted to efficiently hold the cigarettes in place while in the case in order to prevent the cigarettes from being dislodged when the case is opened.

With the above object in view the invention consists of a holder in combination with 20 a case which includes side sections pivotally connected together and means for securing the said sections in closed position, a holder consisting of a tray having suitable compartments therein adapted to receive cigarettes 25 and with means provided at the sides of the compartment for holding the cigarettes frictionally in the same.

In the accompanying drawing:—Figure 1 is a perspective view of a cigarette case 30 showing the sections thereof closed. Fig. 2 is a transverse sectional view of the cigarette case showing the sections open and provided with one form of the holder. Fig. 3 is a plan view of one section of the case showing the 35 form of holder therein as illustrated in Fig. 2. Fig. 4 is a transverse sectional view of a slightly modified form of the holder. Fig. 5 is an edge elevation of a case provided with a plurality of cigarette holders. Fig. 6 is an 40 edge view of another modified form of the holder.

The cigarette case comprises sections 1 which are hingedly connected together and which are provided with suitable securing 45 devices indicated at 2 for securing the free edges of the said sections together when they are in closed positions. A holder 3 is pivoted in one or both of the sections 1 and a spring 4 is interposed between the inner edge 50 of the holder and the inner part of the section and is adapted to bring the holder to

an angular position with relation to the section to which it is attached when the sections are opened. The position to which the holder 3 is brought when the sections are 55 opened is clearly shown in Figs. 2 and 5 of the drawing.

In the form of the invention as shown in Figs. 2 and 3 the holder 3 is in the form of a tray having a series of partitions mounted 60 on the same. The spaces between the partitions 5 constitute compartments within which cigarettes indicated at 6 may be located. Each partition 5 is provided at a point between its ends with an inwardly disposed flexible tongue 7 which is adapted to frictionally engage the side of the adjacent cigarette and hold the same in the compartment in which it is located. In this form of the invention it will be seen that the cigarettes 70 may be readily inserted in the compartments and may be easily withdrawn from the same without danger of tearing the paper of the cigarette or of bending or twisting the same.

In the form of the device as shown in Fig. 4 it will be observed that each partition 5 is provided at its outer portion with a concavity 8 and the side portion of the cigarette is adapted to be received in one concavity and the convex portion of the next adjacent partition 5 bears against the opposite side of the cigarette. Thus the cigarette 80 is securely and efficiently held in place.

In the form of the device as shown in Fig. 6 it will be observed that each partition 5 is provided at its inner edge with a bead 9 and when the cigarette is inserted in the compartment the beads at the partitions 5 which bound the compartments frictionally engage 90 the side of the cigarette and hold the same in position in the compartment. Therefore it will be seen that a simple and durable device is provided for holding cigarettes and at the same time the cigarettes may be easily 95 and quickly withdrawn from the holder.

Having described the invention what is claimed is:—

In combination with a cigarette case a holder hingedly mounted thereon and having partitions located thereon in spaced relation, thereby providing compartments at 100

the opposite sides of the intermediate partitions, each said compartment adapted to receive a cigarette and the partitions adapted to frictionally engage the cigarettes at their opposite sides whereby the cigarettes are held in the holder while it swings upon its hinge connection with the case.

In testimony whereof I, affix my signature in presence of two witnesses.

JOHN NEDERLAND.
